UNITED STATES PATENT OFFICE.

SAMUEL LIONEL JEFFERIES, OF GAFFNEY, SOUTH CAROLINA.

DENTAL CASTING MACHINE.

Application filed January 5, 1922. Serial No. 527,134.

To all whom it may concern:

Be it known that I, SAMUEL LIONEL JEFFERIES, a citizen of the United States, and a resident of Gaffney, in the county of Cherokee and State of South Carolina, have invented certain new and useful Improvements in Dental Casting Machines, of which the following is a specification.

This invention relates to a dental casting machine.

The object of the invention is to provide a machine or device adapted for casting teeth from gold, porcelain or other fusible material in a highly efficient and expeditious manner.

It is also an important object of the invention that the device be extremely simple in construction and easy to manipulate.

Other objects and objects relating to details of construction, combination and arrangement of parts will hereinafter appear in the detailed description to follow.

The invention is illustrated by way of example in the accompanying drawings, in which:—

Figure 1 is a view in side elevation of a form of the present dental casting machine and with parts broken away and shown in section to more clearly illustrate the same.

Figure 2 is a top plan view of the same.

Figure 3 is a view similar to Figure 1 but showing a slightly modified form of the invention.

Figure 4 is a detail plan view of the crucible table shown in Figures 1 and 3.

Figure 5 is a view similar to Figure 4 but showing a slightly modified form of the crucible table.

Figures 6 and 7 are views similar to Figures 4 and 5 and showing two additional modifications of crucible table.

Figures 8, 9 and 10 are vertical sectional views of different forms of casting rings.

Figure 11 is a side elevation of a further modified form of casting ring.

Figure 12 is a side elevation of a casting ring of the type shown in Figure 9 and also illustrating the same within a novel form of receiver pan.

Figure 13 is a bottom plan view of the receiving pan shown in Figure 12.

Figures 14 and 15 are views similar to Figures 1 and 2 respectively, but showing the modification of the invention.

Like reference numerals refer to the same parts throughout the different views.

Referring to the drawings more particularly, B indicates generally the base of the casting machine which may be of any preferred shape, preferably rectangularly as shown, and extending upwardly from a point adjacent the one end of the base is a post 10. The post 10 is preferably square in cross section and the greater portion thereof hollow and within the post there is a sliding extension 11, said extension being square in cross section and the interior of the post 10 being adapted to slidably receive the same and also hold the extension 11 against turning movement. Threaded through the upper end of the post 10 is a set screw 12 whereby the extension 11 may be adjustably held with relation to the post 10. The upper end of the extension 11 terminates in an enlargement 13 which is bifurcated at its free end and provided with a bolt 14, said bolt pivoting or fulcruming a lever bar generally indicated by the reference numeral 15. A free end of the lever bar is connected to the one end of a coil spring 16 while the other end of the coil spring is connected to a hook 17 made secure to the base B. Also the lever bar 15 is formed with an enlargement occurring intermediate the ends of the same as shown, and the purpose of which will later become apparent. The lever bar 15 is also formed with a rounded end portion 19 to serve as a handle therefor. The spring 16 is adapted to normally hold the handle end 19 of the lever bar 15 in raised position with respect to its end connected to the spring 16.

Adjacent the other end of the base B with respect to the post 10 there extends upwardly a pair of supporting rods 20, said rods being threaded at their upper ends through what may be termed a crucible table generally indicated by the reference character T. Also it should be noted that the lower ends of the rods 20 are turnably supported by the platform B and their upper ends are threaded so that the crucible table T may be lowered or raised. The rods 20 support the one end of the crucible table T and as shown one is located adjacent each side thereof while the post 10 supports the other end of the crucible table T. The end of the crucible table associated with the post 10 is formed with a suitable recess through which the post 10 may pass, said recess being centrally of the one end of the table and upon the post there is carried a

collar 21 which is positioned beneath the table T and adjustably held by a set screw 22 so that this end of the table may be raised or lowered, the same as the other end 5 thereof in the manner previously described.

At a point intermediate the ends of the crucible table T there is formed a suitable recess in which there is positioned a grid generally indicated by the reference 10 numeral 23, said grid as shown in Figures 1 and 4, comprising a ring 24 having formed therewith radial plates 25 which extend from its inner periphery to a point in close proximity to the center of the ring. The 15 ring 23 is preferably slightly greater in thickness than the crucible table T and also the upper edge of the ring slightly projects above the radial plates 25. Within the ring 24 there is fitted a cylindrical crucible 26 and about the lower end of the crucible 26 20 is a sheeting of asbestos 27, said asbestos being secured to the table by means of rivets or the like as at 28.

Within the crucible 26 there is positioned 25 suitable sectional molds 28' which are adapted to form a casting cavity as at 29, said casting cavity communicating with the upper surface of the molds through an orifice 30. It will also be observed that the upper 30 surface of the molds 28' are slightly dished as indicated at 31.

A cap 32 is provided which is adapted to fit upon the cylindrical crucible 26 and form a tight closure therefor. The head portion 35 of the cap 32 is provided with a cylindrical extension 33. In the form of the invention shown in Figure 1 this cylindrical extension is partially solid and is fitted in a suitable recess formed transversely of the enlargement 40 of the lever bar 15 and adapted to retain the cap 32 in this position.

Referring to Figure 3 it will be seen that the cylindrical extension 33 is hollow to provide a passage 34 which communicates with 45 the interior of the cap 32. Also it will be seen that a plug generally indicated by the reference numeral 35 is extended into the passage 34, said plug terminating at its outer end in a stop-cock 36 having formed 50 therewith a pressure gage 37. The stop-cock 36 is in turn connected to a flexible hose 38 and valve 39, and said valve 39 with a tank 40 adapted for retaining air under 55 pressure. The stem of stop-cock 35 is rigidly connected to the one end of a link 35', and the other end of link 35' is pivotally connected to a second link 36'. The other end of link 36' is in turn pivoted to the bolt 14 which fulcrums the lever 15.

60 Beneath the crucible table T in both forms of the invention there may be placed a burner 41 and said burner may be properly connected with a supply of gaseous fuel through a flexible hose 42.

65 Referring to Figure 5 it will be seen that

the crucible table T is formed at its one end with a reduced extension 43 through which the post 10 passes, and said extension also carries a set screw 44 by which the extension 11 is adjustably held within the post 70 10. Also in this instance the grid is generally indicated at 45 and is of slightly different construction than specifically shown in Figure 4, said grid comprising a ring (not shown) which is formed with the 75 spokes 46.

In the operation of the device shown in Figures 1 and 2, the gold or other material which is to be used in forming a tooth is to be placed on the mold in the dished surface 31 and then the heating thereof begins. It is of course assumed that the lever bar 15 is in its raised position and so held by the spring 16. The gold or other material will melt and drain into the cavity 29. After 80 the cavity 29 has become filled then wet paper or other suitable material is placed in the cap 32 so as to cover the inner face thereof and then the lever bar 15 is operated for bringing the cap in position for 85 closing the upper end of the crucible 26. This wet paper will force the fused metal or porcelain into the cavity 29 so that the tooth formed will be free of imprisoned air or fissures. 90

In case that a different sized mold or crucible is used then the crucible tables T may be adjusted to suit the same by manipulating the bolts 20 for raising or lowering the one end of the table and adjusting the collar 21 for raising or lowering the other end of the table. Also if necessary the distance of the lever bar 15 above the crucible may be adjusted by means of the set screw 12. 95

In the use and operation of the device 105 shown in Figure 3 the operation is carried on as described for Figures 1 and 2 up to the point when it is desired to force the fused metal or porcelain within the mold cavity 29. The cap 32 is brought into position as shown in Figure 3 and then the stop-cock 36 is opened by the links 35' and 36' and air is permitted to enter the top of the cap with the result that the same air will 110 force the fused metal into the mold cavity 115 and eliminate the possibility of fissures or the like in the tooth formed. Also by this arrangement the pressure of air may be ascertained by the gage 37 and the air may be shut off and turned on from the tank 40 120 by the valve 39.

Referring to Figures 6 and 7 the table, in each instance, generally indicated by the letter T consists in a section of sheet iron preferably rectangular in shape. In Figure 125 6 the table is shown as being formed with a circular opening centrally thereof as at 47 and the pair of enlarged arcuate shaped recesses 48. In Figure 7 a similar central and circular opening 49 is formed in the table T 130

and a plurality of openings 50 are positioned about the opening 49 preferably in the manner shown. In Figures 8, 9 and 10 the casting ring, in each instance is generally indicated by the reference numeral 51, and as shown, consists in a hollow shell tapering toward its lower end. In Figure 8 the shell is shown as formed with a rib 52 adjacent its upper end, while in Figure 9 a similar rib 53 is shown as being formed intermediate the ends of the shell and upon the exterior surface thereof. In Figure 10 the same rib as at 54 is shown as being positioned adjacent the lower end of the shell. Also in Figure 11 a similar casting ring 51 is shown and in this instance intermediate the ends of the ring there is formed upon the exterior surface thereof a plurality of circumferentially spaced lugs 55.

As is obvious either of the casting rings shown in Figures 8 to 11 inclusive may be used upon either of the crucible tables shown in Figures 6 and 7 by positioning the same in the openings 47 and 49 respectively. The purpose of positioning the supporting rib for each casting ring differently is that they may be inserted within the openings 49 or 47 of the crucible tables at different depths.

In Figure 12 there is shown a casting ring of the type shown in Figure 9 and said ring being seated in a receiver pan generally indicated by the reference character 56. This receiving pan 56 tapers toward its lower end and is formed at its upper end with an outwardly projecting flange 57 upon which the rib 53 of the casting ring may seat. The bottom 58 of the receiver pan 56 is formed with a plurality of circular openings 59 in order that the flame may pass upwardly therethrough and within the casting ring seated therein.

Also it may be mentioned that the opening 48 shown in the table 6 is for the purpose of permitting the flame to pass upwardly and about the casting ring and about the opening 50 shown in the Figure 7.

Referring to Figures 14 and 15, the base B in this instance, has two posts 10' extending upwardly therefrom which corresponds in construction to the post 10 shown in Figures 1 and 3, that is, each post is hollow and provided with an extension 13', said extension being slidable within the upper end of the associated post. Also each post is provided with a set screw 12' whereby the extension 13' may be adjustably secured. The table T is supported at its one end in the same manner, as in Figures 1 and 13, that is, by the adjustable rods 20 and at its other end between the pair of posts 10'. The table T has formed adjacent one end a pair of lugs 9, one for each of the posts 10', and each lug being formed with an opening permitting the associated post 10 to slide therethrough.

Also each lug has threaded therethrough a set screw 8 whereby the table 7 may be adjustably held at its one end by the post 10'. Between the upper ends of the post 10' there is turnably supported a cross head 7, and through said cross head 7 there extends the forward end of the lever 15 whereby to fulcrum said lever. The lever 15 is connected with the base B through the means of a coil spring 6, said coil spring being connected at its lower end or to the base by the means of a hook 5. The construction of the dental casting machine shown in these two figures, namely 14 and 15, is otherwise the same as shown in Figures 1 and 2, and it is thought that the operation of this modified form of invention will be clearly obvious without detailed description thereof.

While I have shown and described the preferred form of my invention, I wish it to be understood that I am aware of the fact that the construction, combination and arrangement of parts may be changed by those skilled in the art without departing from the spirit of the invention as indicated by the appended claims.

What I claim is:

1. In a device of the character described comprising in combination, a base, a table supported by said base in spaced relation thereabove, a crucible supported by said table, means for applying a melting heat to said crucible, molds within said crucible whereby the tooth may be cast, a post extending upwardly from said base, a lever bar fulcrumed by said post, a cap carried by said lever bar adapted to be brought to form a closure for said crucible when said handle bar is brought in proper position, means connected with said handle bar to yieldingly hold the same so that the cap is normally disposed above said crucible, and means whereby the table may be adjustably raised and lowered.

2. In combination, a crucible table of the character described, comprising a sheeting of metal having formed centrally thereof a circular opening, a receiving pan cylindrical in shape and tapering toward its lower end adapted to slide within said opening, a flange formed about the upper end of said receiving pan and adapted to engage the crucible table and seating the receiving pan, and a casting ring adapted to fit within said receiving pan.

3. In combination, a crucible table of the character described, comprising a sheeting of metal having formed centrally thereof a circular opening, a receiving pan cylindrical in shape and tapering toward its lower end adapted to slide within said opening, a flange formed about the upper end of said receiving pan and adapted to engage the crucible table and seating the cylindrical pan, a casting ring adapted to fit within

- said receiving pan, and means formed upon the exterior of said casting ring adapted to support the same in spaced relation with the lower end of said receiving pan.
- 5 4. In a dental casting machine, a base, a post extending upwardly from the base adjacent the one end thereof, a pair of rods extending upwardly adjacent the other end of said base, said rods being adapted to be 10 rotated for raising and lowering the same, a table supported between said rods and post, said table being adjustably secured to the post whereby it may be raised and lowered, a lever bar fulcrumed upon said post, a crucible supported by said table carrying a mold, and a cap carried by said lever bar and adapted to be brought into position for engaging said crucible and mold.
- 15 5. In a dental casting machine, a base, a post extending upwardly from the base adjacent the one end thereof, a pair of rods extending upwardly adjacent the other end of said base, said rods being adapted to be 20 rotated for raising and lowering thereof, a table supported between said rods and post and said table being adjustably secured to the post whereby it may be raised and lowered, a lever bar fulcrumed upon said post, a crucible supported by said table carrying a mold, a cap carried by said lever bar and adapted to be brought into position for engaging said crucible and mold, a valve carried by said lever bar whereby compressed air may be injected into the mold upon the cap carried by the lever bar being lowered thereon, and means for automatically opening the said valve when the lever bar is brought to its lowered position.
- 25 6. In a dental casting machine, a base, a post extending upwardly from the base adjacent the one end thereof, a pair of rods extending upwardly adjacent the other end of said base, said rods being adapted to be 30 rotated for raising and lowering thereof, a table supported between said rods and post and said table being adjustably secured to the post whereby it may be raised and lowered, a lever bar fulcrumed upon said post, a crucible supported by said table carrying a mold, a cap carried by said lever bar and adapted to be brought into position for engaging said crucible and mold, a valve carried by said lever bar whereby compressed air may be injected into the mold upon the cap carried by the lever bar being lowered thereon, means for automatically opening the said valve when the lever bar is brought to its lowered position, and a link connection between the post and valve whereby the 35 valve will be automatically opened upon the lever bar assuming its lowered position.
- 35 7. In combination, a crucible table of the character described, consisting in a section of metal sheeting having formed centrally thereof an opening, other openings formed about the first named opening, a casting ring adapted to slidably project into said opening, and means on said casting ring adapted to seat the same upon said crucible table.

SAMUEL LIONEL JEFFERIES.
